INCINERATOR

George Anderson, Chicago, Ill.

Application August 24, 1938, Serial No. 226,462

4 Claims. (Cl. 110—18)

This invention relates to incinerators for the burning of garbage and other waste matter of a combustible nature; and among the objects of the invention are to provide an improved incinerator of that general type wherein the air to support combustion is directed upwardly through vertical air flues in the vertical walls of the combustion chamber, so that the charge burns from the sides toward the middle, instead 10 of the reverse, to provide an improved incinerator that does not require the use of a gas or other burner, or any pit space below the grate, to provide an improved incinerator of the forced draft type, wherein the air entering under forced 15 draft is so directed and controlled as to effect a thorough burning of the refuse, to provide, in association with the main forced draft air supply, a means preferably taking the form of hinged louvers or shutters located above and 20 below the main air supply through which any down draft that may occur is checked, and additional air, whenever needed, is automatically delivered for proper combustion, to provide an improved grate structure that also forms the 25 solid bottom wall of the combustion chamber and has air flues between the grate bars that conduct the forced draft to the lower ends of the vertical air flues in the side and rear walls of the combustion chamber, and to provide an im- 30 proved fire clay lining for the inner sides of the top, bottom and front, rear and side walls of the metal incinerator casing.

Still other objects and attendant advantages of the invention will be apparent to persons skilled 35 in the art to which it belongs from the following detailed description, taken in connection with the accompanying drawings in which I have illustrated a practical embodiment of the structural principles, and wherein—

Fig. 1 is a perspective elevation of the incinerator.

Fig. 2 is an enlarged horizontal section, taken on the line 2—2 of Fig. 1.

Fig. 3 is a vertical front-to-rear section, taken 45 on the line 3—3 of Fig. 2.

Fig. 4 is a transverse vertical section through the bottom wall and grate, taken on the line 4—4 of Fig. 3.

Fig. 5 is an enlarged sectional detail in the 50 vertical plane of the louver controlling the upper auxiliary draft opening.

The shell or casing of the improved incinerator preferably consists of a metal body casting comprising a front wall 10, a rear wall 11, and 55 side walls 12 cast as a unit and formed with

rounded corners 13. Tightly fitted into the bottom of this body structure and spot-welded thereto is an angle iron base ring 14 that constitutes a support for the metal bottom wall 15 of the casing. This latter, as shown in Fig. 3, is horizontal for the most part, but at its forward portion has an upwardly inclined hollow portion 16 that serves to support a correspondingly inclined fire clay platform 17, the top of which registers with the lower edge of a clean-out opening 18 formed in the lower portion of the front wall 10.

Surmounting the body portion of the shell or casing is a dome-type roof that includes a cast metal hollow cover 19, the lower edge of which 15 fits and rests upon the upper edge of the body and is equipped with an internal sleeve 20 secured thereto as by screws 21 that telescopes within the upper end of the body of the casing, this sleeve being attached to the latter as by 20 spot-welding indicated at 22.

In the rear portion of the cover 19 is an opening 23, over which is fitted a collar 24 attached as by bolts 25 that extend through a flange 26 on the member 24 and the cover wall into a body of fire clay lining 27 that fills the greater portion of the cover shell 19. In the forward portion of the cover 19 is a larger opening 28 into which is fitted an angle ring 29 that defines a feed opening, this latter being normally closed 30 by a hinged cover 30 that, by means of a knob 31, can be readily swung to one side or the other to open and close the feed opening. The angle ring 29 is secured in place by bolts 32, similar to the bolts 25, embedded in the fire clay lining 27. 35

The bottom 15 is covered by a horizontal fire clay lining 33, on the top surface of which are parallel fire clay grate bars 34 that extend from front to rear and form between them air passages 35.

The side walls 12 and rear wall 11 are internally covered with fire-proof linings 36 and 37 respectively by means of suitably shaped molds inserted in the body after the bottom lining 33 and its grate bars 34 have been applied. These 45 molds are such as to form vertical air flues 38 and 39 (Fig. 2) in the lining of the side and rear walls that are open at their lower ends to the horizontal flues 35 in the bottom lining, and at their upper ends communicate freely with the 50 open space in the lower portion of the roof or cover.

By the use of suitably shaped molds, there is also cast on the inner surface of the front wall 10 a fire clay lining 40 that includes a substan- 55

tially thickened portion 40', in which latter is molded a chamber 41 that houses an electric motor 42 that operates a direct driven fan 43. To supply air to the fan 43 a portion of the wall covering the rear of the chamber 41 is formed with a circular row of openings 44 (Fig. 1). By reference to Fig. 3, it will be seen that the motor and fan are so mounted as to direct the air in a downward and forward direction directly into the horizontal air flues 35 of the bottom, whence the air flows upwardly through the vertical flues 38 and 39 into the dome or cover, the heated air, products of combustion and acids finding ready vent through the collar 24; the lining 27 having an opening 45 registering with the opening 23. Thus the circulation of air through the combustible material is mainly around the sides of the latter instead of through the center, so that the material burns from the outside inwardly which effects a much cleaner and more thorough combustion and consumption than where the material burns in the reverse direction.

I am aware that it has heretofore been proposed to direct the flow of air and products of combustion from an ash pit upwardly through vertical flues in the front, rear and side walls of incinerators using gas or other burners beneath the grate. My incinerator, on the contrary, is a burnerless incinerator, and combustion is maintained after the refuse has been ignited by a forced draft of air that flows first through the air ducts in the gate and thence through the vertical ducts in the side walls. Should the incinerator contain garbage too wet to burn readily, a short period of operation of the air forcing device, before igniting the material to be burned, sufficiently dries out the material to render it combustible without the aid of gas, oil or other burners.

To so regulate the flow of air as to secure proper combustion, the front wall of the incinerator is equipped with auxiliary inlets for secondary air consisting of upper and lower rows of holes 46 (Fig. 1) and 47. The openings 46 lead into a flaring chamber 48 formed in the lining 40 above the air forcing device, while the openings 47 lead into a flaring chamber 49 formed in a fire clay lining 50 that is molded on the inner side of a clean-out door 51 that controls the opening 18. The door 51 is preferably cast with apertured lugs 52 on its inner side through which is strung a net work of wire 53 for anchoring the fire clay lining 50.

In both of the chambers 48 and 49 are mounted automatically closing hinged louvers 54 and 55 respectively. These louvers open automatically to supply additional or secondary air if required to maintain perfect combustion, while they close automatically to prevent the issuance of smoke or gases through the front wall of the incinerator in the event of back pressure within the latter.

The loaded incinerator is fired by opening the front door 51, pressing the paper and/or other refuse inwardly, igniting it with a match, closing the front door, and then closing the switch (not shown) in the circuit of the motor 42.

Practical experience with the incinerator above described has demonstrated that where the forced draft is used the fire burns into the debris for approximately 100% disposal, leaving only a fine fly ash which from time to time may be cleaned off the grate by opening the door 51 and sweeping the ash out over the platform 17. The

thorough internal lining with fire-proof clay or the like effectually prevents any corrosion of the metal casing from gas or acid erosion, so that the casing maintains its structural integrity and neat appearance for a long period of use.

While I have herein shown and described one practical and improved embodiment of the invention which satisfactorily effectuates the stated purposes and objects thereof, it is evident that changes and variations in minor details may be resorted to without departing from the principles involved, and hence, I reserve all such variations and modifications as fall within the spirit and purview of the appended claims.

I claim:

1. In an incinerator of the class described, the combination with a metal casing, of vertically fluted fire clay linings on the rear and side walls, a horizontally fluted fire clay lining on the bottom wall, the flutes of said latter lining communicating with the lower ends of the flutes of said rear and side wall linings, a dome-type roof having a fire clay lining, and means for forcing a draft of air into and through the flutes of said bottom wall lining and thence upwardly through the flutes of said rear and side walls.

2. In an incinerator of the class described, the combination with a metal casing, of vertically fluted fire clay linings on the rear and side walls, a horizontally fluted fire clay lining on the bottom wall, the flutes of said latter lining communicating with the lower ends of the flutes of said rear and side wall linings, and a motor driven fan mounted on the front wall of said casing at a suitable angle to force a blast of air obliquely downward and into and through the flutes of said bottom wall lining and thence upwardly through the flutes of said rear and side walls.

3. In an incinerator of the class described, the combination with a metal casing, of vertically fluted fire clay linings on the rear and side walls, a horizontally fluted fire clay lining on the bottom wall, the flutes of said latter lining communicating with the lower ends of the flutes of said rear and side wall linings, a fire clay lining on the front wall of said casing, said front wall lining formed with a chamber communicating with the exterior atmosphere through vent holes in said front wall, and an electric motor and fan so mounted in said chamber as to direct a blast of air obliquely downwardly on to said bottom wall fire clay lining.

4. In an incinerator of the class described, a casing having a dome-type roof equipped with a discharge flue, vertically fluted side and rear walls the flutes of which communicate at their upper ends with said roof and serve for the up flow of air and gases, a horizontally fluted bottom wall serving as a grate, the flutes of said bottom wall communicating with the lower ends of the vertical flutes of said side and rear walls, and a front wall formed with vertically spaced air inlets, an air forcing member so mounted on said front wall opposite one of said air inlets as to force the air blast in a downward and forward direction whereby the air flows through the flutes of said bottom, side and rear walls and thence into the roof and through the discharge flue, and hinged louvers mounted on said front wall opposite the other of said air inlets, said louvers opening inwardly of said casing.

GEORGE ANDERSON.
